(57) **CLAIM**

The ornamental design for a paper pallet for a four-wheeled motorcycle, as shown and described.

DESCRIPTION

FIG. 1 is a perspective view of a paper pallet for a four-wheeled motorcycle showing my design;

FIG. 2 is a front elevational view thereof;

FIG. 3 is rear elevational view thereof;

FIG. 4 is a left elevational view thereof; the right side being a mirror image thereof;

FIG. 5 is a top plan view thereof;

FIG. 6 is a bottom plan view thereof; and,

FIG. 7 is a perspective view illustrating use of the paper pallet for a beach car, the phantom lines being for illustrative purposes only and forming no part of the claimed design.
